UNITED STATES PATENT OFFICE.

GEORGE G. POWELL, OF NEW YORK, N. Y., ASSIGNOR TO ANTOINETTE M. POWELL, OF NEW YORK, N. Y.

SALVAGING APPARATUS.

Refile of abandoned application Serial No 259,538, filed October 24, 1918. This application filed March 3, 1923. Serial No. 622,663.

Among the principal objects which the present invention has in view are; to provide means which may be submerged and independently operated to grapple a sunken hull for floating the same; to promote salvage operations without the aid of divers; to promote salvage operations at depths unfavorable for the employment of divers; and to promote salvage operations under atmospheric conditions favorable to men in charge of such operations.

Drawings.—Fig. 1 is a plan view showing the outline of a vessel in position to be salved, and a salvaging apparatus operatively engaging the same, said apparatus being constructed and arranged in accordance with the present invention;

Fig. 2 is an end elevation of the same;

Fig. 3 is a detail view on an enlarged scale showing the operative elements with which the apparatus is provided;

Fig. 4 is an end elevation, partly in section, of the apparatus showing the operative connection between the conning tower and the flotation pontoons;

Fig. 5 is a detail view showing in vertical section, the valve for controlling the air supply of said apparatus.

Description.—As seen in the drawings, the apparatus preferably consists of two units and a control station operatively connected with said units. Each unit is constructed substantially as shown in Fig. 2 of the drawings, to provide a number of curved tong-like members, and operating instrumentalities connected therewith. The tongs are arranged in pairs, said pairs being connected by pivot shafts 8. Each member of the tongs embodies an enlarged gripping arm 9, at the extremity of which is a hook like extension 10. The arms 9 are preferably hollow, the structure thereof being designed for strength with lightness. Each of the hook-like extensions 10 has jetting openings 11 and 12. The openings 11 are disposed in what may be termed the nose of the extension 10, and are provided to direct an air or water jet in advance of the ends of the arms 9. The openings 12 co-operate therewith for clearing the area below the ends of the arms to permit the same to sink into ooze on the sea bottom on which the wreck rests. As seen best in Figure 2 of the drawings, the arms 13—13 and 9—9 are hollow

and can function both as jetting and buoyant devices as explained hereinafter.

Each arm 9 is structurally and rigidly connected by a lever arm 13, to one of the two pontoons 14. The pontoons are divided by a series of bulkheads 22 into compartments for ballasting. Each compartment has a bottom opening 15, through which water is emitted or admitted. The bulkheads 22 are located under each lever arm 13 for strengthening the pontoons 14 and to form a plurality of compartments.

The chamber 16 is designed to hold one or more operators, the walls of said chamber being so constructed as to resist the hydrostatic pressures when atmospheric pressure is maintained in the chamber.

Air for operating the pontoons 14 and jetting from the arms 9, is supplied from the flasks 17, which are charged with air compressed to a high degree. The flasks 17 may be carried in any part of the structure, the space in the pontoons 14 being found best suited, and for that reason is shown in the disclosed structure. It will be understood, however that the flasks may be strapped or otherwise secured to the back or upper edge of the lever arms 13. The flasks are connected by means of a flexible pipe to the chamber 16, and to a master controlling valve or manifold provided therein. A distributing system of pipes 19, 20 and 21 permits the operator in the chamber 16 to control the action of the pontoons.

Salvaging apparatus is brought directly over the previously surveyed and buoyed wreck. Buoyed anchors connected to winches located on each end of each lifting pontoon 14 (not shown) are carried to and sunk at four equidistant points. These winches are controlled from the chamber 16 and provide positive and accurate means for guiding the apparatus to bring the grappling arms 9—9 in alignment with, and to pass on each side of the wreck, and also to positively sink the apparatus against a slight retained buoyancy in the lifting pontoons 14.

At the beginning of the operation, it will be seen that the pontoons 14 are filled with air to float on the surface of the water, and to swing the arms 9 toward each other. The couples having been operatively connected, the air in the pontoons is withdrawn permitting water to enter through the openings

15. As the pontoons sink, the levers 13 and arms 9 connected therewith are rocked on the shaft 8 to the open position of the said arms. The whole structure sinks together, 5 no communication being maintained with the surface except telephonic communication.

The outspread arms 9—9 pass in controlled alignment the sides of the submerged wreck, the extensions 10 resting upon the seat bottom. 10

By manipulating the proper valves 23, hereinafter described, the operator exhausts the compressed air from the interior of the tong members 13—13 and 9—9, which has 15 maintained them in their open position, and thereby permits any desired proportion of their combined weight to force their bottom ends 10 into the sea floor and partially close under the bottom of the object to be raised, 20 assisted by the jets that issue from the jet holes 11 and 12. By this means the ooze of the sea floor is removed from the path of the feet 10.

The weight of the couples 9—9 resists the 25 lifting action of the pontoons 14—14. Therefore, when air is forced into the top of the pontoons 14—14 from the pipes 20, their lifting value is first expended in the further closing of the couples 9—9 and continued, until 30 the united flotation of the pontoons 14 lifts the wreck from its bed to the surface of the water.

In the salvaging operation performed by this apparatus, it is intended that the wreck 35 shall be lifted until the upper deck is awash, with the bulwarks sufficiently above the surface to act as a cofferdam. Then the ordinary salvaging methods, as closing all openings in the hull, pumping out and releasing 40 the salvaged vessel from the lifting apparatus, are completed.

It will be understood that the air by which the apparatus is operated is supplied through the instrumentality of the flasks 17. It will 45 be further understood that the air is delivered to or permitted to escape from any of the various compartments formed by the bulkheads 22 in the two pontoons. In this way every end of each of the pontoons is depressed or elevated relative to the opposite end, and in this manner permitting the operator in the chamber 16 to adjust the salvage apparatus to the wreck, and to compensate any shifting of weight of cargo that may have 50 occurred to allow rising to the surface on an even keel.

Referring to Figs. 4 and 5, the operating chamber 16, is provided with a pair of valves 23, each of which may be manipulated by its 55 hand wheel 24. As indicated in Fig. 5 each of the valves 23 comprises a rotary plug. The casing of the valve has formed therewith a series of ports to which the pipes 18, 20, 19, 21 and 26 are connected. To register with 60 said ports the plug in the valve 23 is pro-

vided with a vertical port from which extend the radial ports. The radial ports 28, 29 are located to connect with the pipes 18 and 20 simultaneously. When the valve plug is turned to open communication with the pipes 18 and 20, the compressed air in the flasks 17 is delivered to the pontoons 14 to eject the water therefrom, to increase the floatation of the same. When the ports 30 and 31 are registered with their corresponding port 70 openings the pipes 20 and 26 are opened to permit the air formerly held in the pontoons to escape. When the plug of the valve 23 is turned to register the ports 32 and 33 with their corresponding openings, the pipe 18 is placed in communication with the pipe 19, with the result that compressed air is delivered into the hollow arms 13, for the purpose of blowing the water enclosed through the openings 11 and 12, and also for increasing the floatation of the arms 9—9 and 13—13, by the exclusion of water therefrom. When the plug of the valve 23 is turned to register 80 with the ports 34, 35, the pipes 19 and 21 are placed in communication to permit the air to escape from the arms 9—9, 13—13. 85

Standard instruments used in submarines and abroad ship are used and the control chamber 16 is equipped with inclinometers, air manifolds for the distribution of the compressed air from flasks 17, gyro-compass for orientation underwater, are all similar to those used in the submarine. 90

It will be understood that various modifications may be made in the invention without departing from the spirit thereof and the present exemplification is to be taken as illustrative and not limitative thereof. 100

Having described my invention what I desire to secure by Letters Patent and claim is: 105

1. A salvaging apparatus comprising elongated pontoons, the length of said pontoons being approximately that of the wreck to be salvaged, a series of hollow tong-like members extending between said pontoons and having one of their ends rigidly secured to the same, means for pivotally connecting said hollow tong-like members intermediate said pontoons, means for carrying air under pressure in said pontoons, means for releasing air within said pontoons, means for carrying air under pressure to said hollow tong like members, means for releasing air from said hollow tong like members, a central station to which all of both said means is operatively connected, said air permitting the admission of water and ejection thereof from said pontoons and said hollow tongs whereby the specific gravity of the same may be varied, and means dividing said pontoons into compartments. 110 115 120 125

2. In a salvaging apparatus the combination of a plurality of pairs of hollow pivoted displacing members, the members of each pair oppositely positioned, each member hav- 130

- ing formed at one end a hollow tong arm integral therewith, a pair of pontoons in the salvaging apparatus, and the member of each of said pairs at the end opposite its hollow tong arm rigidly connected with one of said pontoons, the interior of each pontoon separated from the interior of said member. 5 and arms whereby to render them buoyant.
7. Salvaging apparatus, including hollow tongs pivotally secured together, hollow arms connected to such tongs, pontoons connected to the outer end of the arms, the lower ends 60 of the tongs being provided with inwardly projecting and opposing extensions, said tongs being adapted to receive buoyant fluid, means to eject the buoyant fluid from the tongs, and to form jets of fluid to assist the 65 opposing extensions to burrow into the sea floor and under the object to be salvaged.
8. Salvaging apparatus, including hollow tongs pivoted together, arms secured to the upper ends of such tongs, and pontoons 70 secured to the outer ends of such arms, the tongs being adapted to extend around and engage the object to be raised, the arms being so arranged with respect to the tongs, and such pontoons being in turn arranged with 75 respect to such arms, that the upper edge of the object to be raised will project above the surface of the water.
9. In a salvaging apparatus the combination of a plurality of pairs of hollow pivoted 80 displacing members, the members of each pair oppositely positioned, each member having formed at one end a hollow tong arm integral therewith, a pair of pontoons in the apparatus and the member of each of said pairs 85 at the end opposite its hollow tong arm rigidly connected to one of said pontoons, bulkheads in each pontoon forming compartments therein, a plurality of flasks in connection with each other in each of said compartments, 90 an operating chamber capable of being submerged adjacent to the displacing members, a pair of valves in said operating chamber, piping extending from said valves to the flasks of each pontoon to distribute compressed air from said flasks, piping leading 95 from each of said valves to each compartment of each pontoon to direct the distributed air into the latter, and piping leading from said valves to direct the distributed air to the hollow displacing members, piping connected to each valve to discharge the air from each compartment in the pontoons and piping connected to each valve to discharge the air from each of said displacing members. 100
- Signed at the borough of Manhattan, city of New York in the county of New York and State of New York this 2nd day of March A. D. 1923.
